UNITED STATES PATENT OFFICE.

OTTO EDWARD ENELL, OF JERSEY CITY, NEW JERSEY, ASSIGNOR TO UNIQUE
SPECIALTY CO., INC., A CORPORATION OF NEW YORK.

STOPPLE ATTACHMENT.

1,184,335.

Specification of Letters Patent.

Patented May 23, 1916.

Application filed January 10, 1914. Serial No. 811,490.

To all whom it may concern:

Be it known that I, OTTO EDWARD ENELL, a citizen of the United States, and resident of Jersey City, in the county of Hudson 5 and State of New Jersey, have invented certain new and useful Improvements in Stopple Attachments, of which the following is a specification.

The present invention relates in general 10 to the mounting of supplementary receptacles, such as may be used in connection with containers of various sorts, and more particularly to means whereby the supplementary receptacle is adapted to be carried 15 by the stopple of the container.

One object of the invention is to produce a simple, neat and convenient device of the kind above referred to providing a desirable support for a dip-cup or well attached 20 to the stopper of an ink-bottle or similar reservoir for fluids.

Another object is to provide an inexpensive attachment for the purpose in view which will be of a substantial nature and 25 will also impart the requisite strength and durability to the stopper itself.

Still another object is the provision of means removable from the attachment for transferring the ink or other fluid from the 30 bottle or reservoir into the cup or well, or the reverse as may be required.

A further object is the production of an attachment comprising a plurality of separable parts, permitting independent manipulation thereof, such, for instance, as the removal of the dip-cup for cleaning without disturbing the ink-bottle or its stopper.

Other objects and advantages will become apparent as the specification proceeds.

With the aforesaid objects in view, the invention consists in the combinations and arrangements of parts hereinafter described, pointed out in the subjoined claims, and illustrated in their preferred embodiments 45 in the accompanying drawings in which:—

Figure 1 is a sectional elevation of one form of the attachment as it appears when applied to an ink-bottle, the latter being shown in dotted lines; Fig. 2 is a top plan view of the same form of the attachment, certain parts being omitted; Fig. 3 is a vertical section of a modified construction of the attachment; Fig. 4 is a top plan view of the latter named construction; Fig. 5 is a side elevation of another modification of the

invention, the stopper being shown in section; and Fig. 6 is a top plan view of the last named modification, parts being omitted.

Referring now particularly to Figs. 1 and 2, the numeral "11" designates a stopper of familiar design, consisting of a conical cork adapted for insertion in the neck of a bottle so as to project partly thereabove, as indicated in the drawing.

On the top or upper surface of the cork 11 is a slightly larger plate 12, of similar configuration, and having a laterally extended arm 13, which terminates in a smaller plate 14, also of like outline. By preference, the combined plates and arm here referred to are made of pressed metal, in one piece.

A continuous flange 15 is formed around the said arm and plates depending therefrom so as to impart the required rigidity to the construction, besides affording a convenient means in the shape of an inverted socket for securing the plate 12 to the upper part of the cork 11 which is effected by crimping the flange, that is, turning it inward and pressing it into the cork laterally. As an additional means for fastening it firmly to the cork and preventing its displacement thereon, tongues 16 are punched out of the plate 12, in opposite directions and forced downwardly into the top of the cork.

The plate 14 is formed with a central aperture or socket in which is loosely fitted a dip-cup or small ink-well 18. The latter has a flange 19, by means of which it is suspended from the surface of the plate. This cup or well may be made of metal or other non-absorbent material, as glass, porcelain and the like.

In the center of the plate 12, is also provided an aperture 20, through which passes an ink-dropper, consisting of a glass tube 21, loosely fitted in this aperture and provided at its upper end with an india rubber bulb or nipple 22. A corresponding aperture is bored axially through the cork 11, to enable the tube 21 to enter the bottle and be immersed normally in the ink contained therein, while the bulb 22 remains upright outside the plate 12, on which it may rest at the base, the latter being of sufficient size to stop hermetically both said apertures and thus form a closure for the same as also for the bottle. Where it is deemed advisable,

the aperture in the cork may be lined with a tube 17, flanged over the head 12, and the underside face of the cork thereby tying these parts together.

5 It will now be readily perceived that, by manipulating the ink dropper in the accustomed manner, it requires but a moment's work to take out of the bottle the small quantity of ink required and fill the dip-cup 18 therewith, or else to transfer the ink back from the latter into the former. No ink other than what is deposited into the dip-cup need be exposed to the oxidizing action of the atmosphere, and therefore the contents of the bottle can be preserved in a perfect state until they are all consumed. Whatever may remain in the dip-cup after a day's use may either be returned to the bottle by means of the dropper or thrown 15 away in cleaning out the dip-cup, and otherwise there is no waste nor deterioration of the ink stored in the bottle.

In Figs. 3 and 4 is shown a modified form of the attachment, wherein the support for 20 the dip-cup 18 is somewhat varied in contour, though including practically the same number of elements and discharging the same functions as the one previously described herein. This support consists of an 25 approximately pyriform plate 12^a, which may be made of wood fiber or analogous composition affording a smooth surface on which may be placed any desired inscription or advertising matter. The larger part of 30 the plate, bearing the reference character 12^a, is hollowed out on the underside, as at 23, to form therein a recess or socket adapting it for a snug fit upon the upper end of a cork 11^a. At one side of this recess, the plate 35 is narrowed evenly on both sides into a lateral extension 13^a, which terminates in a somewhat tapering, rounded portion 14^a, having also a suitable aperture or socket to receive the flanged dip-cup 18. No aperture, 40 it will be noticed, has been shown in either the cork 11^a, or the overlying part of the plate 12^a, such as Figs. 1 and 2 disclose for the reception of the ink dropper, but it is 45 understood that the detail in question can be supplied if desired.

Figs. 5 and 6 illustrate an attachment made entirely of wire, which is bent and twisted to constitute a loop 12^b, with a laterally projected arm 13^b, terminating in a 55 smaller loop 14^b. The larger loop 12^b is designed to encircle tightly the upper end of a cork 11^b, serving as a socket therefor, while the loop 14^b, provides a seat for the removable dip-cup 18. A complementary loop 24, 60 formed integral with 12^b, acts as a retainer by bearing upon the top of the cork and preventing the attachment from sliding down the body of the latter. The loop 24 possesses sufficient resilience to clamp its master-loop 65 12^b, to the upper end of the cork. Now,

when it is desired either to apply the loop 12^b to, or detach it from, the cork, the sides of the companion loop 24 are pressed together, thereby causing the main loop 12^b to expand readily so as to enable it to be put in or taken off the cork, as required. The ends of the wire from which this form of attachment is composed are twisted together in the arm 13^b, intermediately of the loops 12^b, 14^b and meet centrally therein, as at 25, 75 for example.

Although the herein disclosed improvements have been described specifically with reference to an ink bottle and the cork thereof, it is manifest that they are applicable as 80 well to other containers. It is further obvious that several changes or alterations can be effected in the attachments described, without departing from the basic principle of the invention. Therefore, I do not wish 85 to be understood as restricting the scope of this invention to the specific means for carrying into practice involved in the present disclosure, but desire to reserve fully 90 the right to all modifications and equivalents that come fairly within the appended claims.

Having described my invention, what I desire to secure by Letters Patent and claim is:—

1. An attachment for ink-bottles comprising in combination a stopple, a plate overlying said stopple, an arm extending laterally from one side of said plate substantially in the same horizontal plane as the latter, 100 said arm being provided with an aperture, a flanged supplementary ink-receptacle removably seated in said aperture having the flange thereof overlying the arm, and means for securing the plate to the stopple. 105

2. The combination with an ink bottle, of a stopple therefor, a socketed support secured to the top of said stopple, an arm formed with said support overhanging the neck of the ink bottle, said arm being provided with an aperture offset from the center of said support, a supplementary ink receptacle seated in said aperture, and means transferable from the stopple for bringing ink from the bottle to said receptacle and 115 from the latter back into the bottle while the latter remains in an upright posture.

3. The combination with an ink bottle, of a stopple therefor, a support overlying the top of said stopple, an arm extending laterally over the neck of the bottle from the side of said support, said arm being provided with an aperture centrally offset from the axis of the stopple, a sleeve passing through the latter having its lower end upset to secure the support to the stopple, a supplementary ink receptacle seated in said aperture, and a dropper detachably received in said sleeve adapted for transfer of ink from the bottle to said supplementary receptacle 130

and from the latter back into the bottle, the upper portion of said dropper forming a closure for the sleeve.

4. An attachment for ink-bottles, comprising in combination a stopple having a vertical bore, a laterally extended support overlying said stopple formed with an opening registering with the bore thereof, a supplementary ink receptacle removably seated within the extension of said support, and a detachable dropper stopping said bore capa-

ble of transferring ink from the bottle into said supplementary receptacle and back from the latter into the former.

Signed at the borough of Manhattan, in 15 the county of New York and State of New York this 7th day of January, A. D. 1914.

OTTO EDWARD ENELL.
